[57] CLAIM

The ornamental design for a shopping bag, as shown and described herein.

DESCRIPTION

FIG. 1 is a front perspective view of a shopping bag showing my new design;

FIG. 2 is a rear perspective view;

FIG. 4 is an elevational view looking from the right of FIG. 3 the opposite side being the mirror image of the side shown;

FIG. 5 is a rear perspective with the bag in closed position and the carrying strap loosened for use;

FIG. 6 is a front elevational view thereof; and

FIG. 7 is a bottom view thereof.

The broken line showing of a cart in FIGS. 1 and 2 is for illustrative purpose only.
